ATTORNEYS

UNITED STATES PATENT OFFICE.

FRANK B. PARKER, OF ROBINSON, KANSAS.

WRENCH FOR AUTOMOBILE PARTS.

Application filed December 11, 1922. Serial No. 606,157.

To all whom it may concern:

Be it known that I, FRANK B. PARKER, a citizen of the United States of America, and a resident of Robinson, in the county of 5 Brown and State of Kansas, have invented a new and Improved Wrench for Automobile Parts, of which the following is a description.

My invention relates to a wrench and 10 more particularly to a wrench for turning certain parts of an automobile, particularly of the Ford type.

The general object of my invention is to embody in a unitary wrench device a means 15 adapted to variously engage the parts to be turned such as the cap of a gasoline tank, the radiator tank and the oil petcock for testing as to the oil in the crank case.

Reference is to be had to the accompanying 20 drawings forming a part of this specification, it being understood that the drawings are merely illustrative of one example of the invention.

Figure 1 is a perspective view of a wrench 25 formed in accordance with my invention;

Fig. 2 is a plan view thereof on a reduced scale; and

Fig. 3 is a longitudinal vertical section on the line 3—3, Fig. 2.

30 In carrying out my invention in accordance with the illustrated example a wrench head is provided having an elongated approximately flat intermediate portion 10, the front upturned end 11 of which in practice

35 is advantageously directed rearwardly on an oblique line to partially overhang the intermediate member 10 while at the rear end of the member 10 the head rises as at 12.

Integral with the rear upwardly extending 40 member 12 is a seat 13 having at each side an elongated lug, 14, the lug being undercut to present an overhanging portion, so that the lugs constitute guides to form with the seat 13 a socket for a flat handle 15 which 45 in practice may consist of a rule for measuring gasoline, the forward end of which is accommodated on the seat and engaged by the guide lugs 14.

The head is provided with a longitudinal 50 slot 16 in the intermediate portion 10 and at opposite sides about equal distance from the

upwardly extending members 11, 12, the slot 16 is widened as at 17. At the front end the slot is continued as at 18 in the upwardly extending member 11 and at the rear end of 55 the head said slot is continued upwardly through the rear member 12. The slot 16 with more or less of the upwardly extending slot members 18, 19 accommodates the vertical flange members on the cap of a gasoline 60 tank while the widened portion 17 of the longitudinal slot 16 will accommodate and cause the head to engage one of the horns on the radiator caps of a certain make. The slot at the upwardly extending end 18 serves 65 to receive the handle of the petcock on the crank case for turning said petcock for testing as to the amount of oil in the crank case.

I would state in conclusion that while the 70 illustrated example constitutes a practical embodiment of my invention, I do not limit myself strictly to the exact details herein illustrated, since, manifestly, the same can be considerably varied without departure 75 from the spirit of the invention as defined in the appended claims.

Having thus described my invention, I claim:

1. A wrench of the class described including a head having upturned front and rear 80 ends formed with a slot longitudinally of said head and extending into said upturned ends, said slot between the upturned ends being widened approximately equidistant from said ends.

2. A wrench of the class described comprising a longitudinally slotted broad intermediate portion, and upturned ends into which the slot is continued, and a handle engaging means extending rearwardly from 90 the upturned rear end.

3. A wrench of the class described comprising a longitudinally slotted broad intermediate portion, and upturned ends into which the slot is continued, and a handle engaging means extending rearwardly from the upturned rear end, said handle engaging means comprising a seat plate and longitudinal overhanging lugs at the sides of 95 said plate and forming with the latter a 100 socket for the handle.

FRANK B. PARKER.
